UNITED STATES PATENT OFFICE.

HANS OVE LANGE, OF COPENHAGEN, DENMARK.

REISSUED

PILLOW AND CUSHION AND CASING FOR SAME.

Application filed February 24, 1928, Serial No. 256,758, and in Denmark December 24, 1927.

The invention refers to a pillow, sofa-cushion and the like, and a casing for same.

The invention consists in the pillow's casing having superposed pockets decreasing in size upwards and/or downwards from a main pocket.

The attached drawing shows:—

Fig. 1 a side view of a pillow as per invention

10 Fig. 2 the same as seen from above

Fig. 3 a cross section of same, and

15 Fig. 4 a cross section of a different style of execution as per invention.

In the pillow as per Figs. 1-3, the filling material is put into three superposed pockets *a*, *b* and *c*, decreasing in size in the direction from the pillow's back towards its front. The pillow shown by Fig. 4 has likewise three pockets, *d*, *e* and *f*, but in this case the 20 middle pocket *d* is the biggest, while the pockets at the top and bottom, respectively *e* and *f*, are smaller.

The pockets of the pillow can be filled either with the same or with different materials. For pillows it would in general be preferable to put into the largest pocket a 25 strong elastic filling material of good carrying capacity, e. g. bed feathers, curled hair or kapok, in the next pocket a light half 30 down, and in the third and smallest pocket, if any, a down.

As shown by the drawing, the pillow is made with two or more superposed pockets, decreasing in size from a main pocket which 35 can be situated either at the bottom or in the centre of the pillow, or in general can be any of the pockets in the pillow. The walls between these pockets can be single or double and the pieces of cloth are sewn or in some 40 other way fastened to each other. The pockets serve for receiving the filling material.

The pillow as per invention distinguishes 45 itself by keeping the filling material in place, and because it can be filled with different kinds of such materials according to the various purposes for which it is to be used, advantages not attained by the kind of pillows known up to now.

50 In pillows consisting of one pocket only, the filling material during use is forced towards the edges, with the result that the centre of the pillow offers but deficient support. This is obviated by the invention, inasmuch 55 as the shifting of the filling material is restricted within each separate pocket. When

an ordinary pocket, in order to give a specially soft support, is stuffed with a fine material, for instance down, it is apt to double up under the weight of the head, a drawback 60 which especially in summer time or in warm climates can produce insomnia and on the whole is unhealthful. In the pillow as per invention, these drawbacks are overcome, as the smallest pocket only is meant to be filled 65 with down and the remaining pockets with less heat insulating materials possessing greater carrying capacity. For this reason the pillow as per invention is particularly suitable for use in hospitals, and the danger 70 of placing babies on soft down pillows folding up around the head, is obviated.

A pillow executed as shown by Fig. 4 possesses moreover the advantage that one side can be stuffed for winter use and the 75 other one for summer use, by filling pocket "e" with a heat-insulating material, for instance with down as being most suitable for use in winter, whereas pocket "f" when filled with a less heat-insulating material as for instance the soft part of feather vanes, gives a 80 soft but cooler support for the head in summer time, which particularly is of advantage in countries with considerable variations of 85 temperature.

In spite of the above mentioned important properties, the pillow can be produced at a lower price than the ordinary kind of pillows used up to now, as for the largest pocket a coarser and cheaper quality of feathers can 90 be employed which moreover has the advantage of being stronger and possessing greater resiliency and carrying capacity. Of the dearer qualities of half down and down intended for the smaller pockets, a minor 95 quantity only is required in comparison to the total weight of the filling material. The casing or covering likewise can be made cheaper, a down proof fabric being required only for the comparatively small portion of 100 the pillow which is to contain down, while as casing for the coarser filling material which forms the greater portion of the pillow, a considerably cheaper fabric can be employed.

The invention is not restricted to the styles of execution shown and described above, as they can be altered in different ways, especially as regards number, size and shape of the pockets, without exceeding the scope of 110 the invention.

Having thus fully described my invention,

I claim as new and desire to secure by Letters Patent:

1. A pillow of the kind adapted to be used as a bedding pillow, sofa cushion or the like, consisting of a casing and filling material, said casing composed of a main pocket and a series of superposed pockets sewed on top of said main pocket, said superposed pockets decreasing in size from the main pocket.

2. A pillow of the class described, consisting of a main casing filled with coarse material, a series of superposed pockets of decreasing size sewed on the top of the main pocket, said pockets of decreasing size filled with fine soft material.

In testimony whereof I have affixed my signature.

HANS OVE LANGE.
